UNITED STATES PATENT OFFICE.

WRIGHT KNAPP, OF EVELAND GROVE, IOWA.

MACHINE FOR WINDING AND TIGHTENING FENCE-WIRES.

SPECIFICATION forming part of Letters Patent No. 357,209, dated February 8, 1887.

Application filed August 19, 1886. Serial No. 211,289. (No model.)

To all whom it may concern:

Be it known that I, WRIGHT KNAPP, a citizen of the United States, residing at Eveland Grove, in the county of Mahaska and State of Iowa, have invented a new and useful Improvement 5 in Machines for Winding and Tightening Fence-Wires, of which the following is a specification.

My invention relates to an improvement in 10 machines for winding and tightening wires for wire fences; and it consists in the peculiar construction and combination of devices that will be more fully set forth hereinafter, and particularly pointed out in the claim.

15 In the drawings, Figure 1 is a perspective view of a device embodying my improvements in position for winding the wire from an old fence. Fig. 2 is an elevation of the same, showing the opposite side from that represented in Fig. 1. Fig. 3 is a vertical longitudinal sectional view of the machine for winding and tightening wires, and an elevation, partly in section, of the clamping device, showing the manner of using the apparatus for stretching a wire. Fig. 4 is a detail 25 perspective view of the clamping device.

A represents the machine for winding and tightening wires, which comprises a rectangular frame, B, having supporting wheels or 30 rollers C. From the center of the frame project vertical standards D, which are provided with inclined braces E. These standards are made with a series of transverse openings, F.

G represents a horizontal shaft which is 35 journaled in two of the openings F of the standards D, and one end of the said shaft forms a spindle adapted to receive a crank-handle, H. Near the said end of the shaft, and on the outer side of one of the standards 40 D, is a ratchet-wheel, I. A pawl, K, is pivoted to the standard and engages the ratchet-wheel. On the opposite end of the shaft G is a friction drum or pulley, L, which is attached to the shaft by a transverse pin, M, and is thus 45 easily removed from the shaft by first withdrawing the said pin. To the central portion of the shaft G, between the standards, is attached a removable spool, N.

O represents a brake-lever which is pivoted 50 to the frame and is adapted to bear against the friction pulley or drum, for the purpose to

be hereinafter described. Under the front end of the frame, at the center thereof, is pivoted a detent, P, which is adapted to be forced into the ground, so as to prevent the reel-frame from moving when a wire is being stretched. This detent has an arm, P', which is adapted to strike against a cross-bar, P'', at the front end of the frame, to prevent the detent from turning on its pivot after it is forced 55 into the ground and when the machine is under strain, thus holding the machine firmly in place while the wire is being stretched.

R represents a clamp comprising a pair of jaws, S and S', which are pivoted together, 60 and are provided with arms S''. On one side of the jaw S' is a shoulder or offset which is provided with a series of teeth or corrugations, a, and the edge of the opposing jaw, S, is provided with a depending flange, b, which 65 is adapted to close upon the outer side of the said teeth.

c represents a link which connects the arms S'' together, and the said link is adapted to slide back and forth upon the arms. When 70 the link is forced to the outer ends of the arms, it serves to lock the jaws in a closed position.

d represents a rope which is attached to the outer ends of the arms S''.

The operation of my invention is as follows: 80 When it is desired to reel the wire from a fence which is to be taken down, one end of the wire is attached to the spool N and the reel-frame is placed on the ground. The shaft G, carrying the spool, is rotated by means of its crank-handle, thus winding the wire from the fence onto the spool, as will be very readily understood. As the wire is wound upon the spool the reel-frame advances on the ground by reason of its supporting-rollers. In order to prevent the wire from being loosely reeled upon the spool, the brake-lever O is applied to the friction drum or pulley by forcing the said lever up against the under side thereof. This 85 prevents the spool from rotating too freely, 90 and causes the wire to be wound upon the spool compactly and with sufficient tension.

In order to stretch a wire which is being attached to the fence-posts, the spool is first removed from the shaft G by removing the friction drum or pulley from the said shaft, and then withdrawing the latter from the stand- 100

ards D. The friction-drum and the shaft are then replaced in position, and the reel-frame is secured against moving by causing the detent to engage the ground on which the frame 5 stands; or the latter may be placed in a wagon, or fastened behind the same. The wire to be stretched is clamped between the jaws S and S' of the clamping device, and the free end of the rope which is attached to the arms of the 10 clamping device is secured directly to the shaft G in any suitable manner. The shaft is then rotated in the direction indicated by the arrow in Fig. 3, thus causing the wire to be stretched, as will be very readily under- 15 stood.

Having thus described my invention, I claim—

In a machine for stretching fence-wires, the combination of the reel-frame and the detent pivoted thereto and adapted to engage the 20 ground, the said detent having the arm P', to bear against the reel-frame and thereby prevent the detent from turning when the machine is under strain, substantially as described.

In testimony that I claim the foregoing as my 25 own I have hereto affixed my signature in presence of two witnesses.

WRIGHT KNAPP.
